UNITED STATES PATENT OFFICE.

CHARLES R. BROWN, OF MINNEAPOLIS, MINNESOTA, ASSIGNOR OF ONE-HALF TO
WILLARD STOWELL, OF ST. PAUL, MINNESOTA.

ATTACHMENT FOR PLATEN PRINTING-PRESSES.

1,376,187.

Specification of Letters Patent. Patented Apr. 26, 1921.

Application filed June 5, 1919. Serial No. 301,940.

To all whom it may concern:

Be it known that I, CHARLES R. BROWN, a citizen of the United States, residing at No. 1820 4th street southeast, Minneapolis, Hennepin county, Minnesota, have invented a new and useful Attachment for Platen Printing-Presses, of which the following is a specification.

My invention relates to improvements in 10 perforating, cutting and scoring devices operated with platen printing presses in which the perforating, cutting or scoring blade and ejector are held in position to function with the operating of the press, 15 without injury to the inking rolls, by being fastened to metal clamps which are attached to the grippers of the press, being held in proper position by the tension of said metal clamps after the grippers are set at their 20 correct positions, and a metal base locked in the form in the chase of the press.

My objects are first to provide a perforating, cutting and scoring attachment which will successfully operate simultaneously 25 with the printing operation without injury to the inking rolls; second to so construct the attachment that it may be applied and adjusted to produce a perforated, cut or scored line between any two printed lines as 30 close together as one sixth of an inch if desired; third to so construct the attachment that by attaching it to the grippers in the manner stated it will act as an auxiliary gripper and ejector with the operation of 35 the press; fourth to so construct it that it may be attached to any platen printing press easily, quickly and substantially, but without the use of special tools or appliances; fifth, to so construct the device that it will 40 be possible to perforate, cut or score any length of line from one inch up to and including a line of the total length of the active edge of the blade.

I accomplish these by the mechanism illustrated in the accompanying drawings; Figure 1 is a broad side view of the perforating blade. Fig. 2 is a view of the backs of the perforating blade and the ejector fastened to metal clamps, attached to the grippers. Fig. 3 is a broad side view of the perforating blade and ejector with fastenings to the cross section of the metal clamps and cross section of the grippers. Fig. 4 is a partial broad side view of the metal base, the perforating blade and the ejector with con-

nections to the cross section of one metal clamp and cross section of one gripper. Fig. 5 is a sectional end view of the perforating blade and ejector with their fastenings to one metal clamp in position on 60 gripper. Fig. 6 is a cross section view of a portion of a platen printing press partially open, showing an end view of my attachment on the grippers in its relative position to the metal base locked in the form 65 in the chase secured to the bed of the press, and the relative positions of the platen and the bed of the press. Fig. 7 is a cross section view of the same portions of a platen printing press and my attachment, with the 70 press in a closed position.

Similar numerals refer to similar parts throughout all views. The perforating blade (1) is made of thin, highly tempered steel, one edge of which is finished with 75 milled, sawed or stamped teeth. The cutting blade is made of the same material and of the same thickness, but is finished with a sharp knife edge in lieu of the perforating teeth shown. The scoring blade is made of 80 the same material and of the same thickness, but is one seventy second of an inch narrower and is finished with a dull knife edge in lieu of the perforating teeth shown. The three blades and their connections are 85 alike, except as just noted, and for brevity I will deal herein with the perforating blade (1) shown. In one end of the blade (1) I use a slotted hole with a round hole in the opposite end, which is as I prefer to 90 make them, but either type of holes may be furnished in both ends. The blade (1) may be any length desired for the press with which it is to be used, and is fastened to the upper half of the metal clamps (3) by 95 cotter pins engaging the holes shown in Fig. 1. The ejector (2) is fastened to the lower half of the metal clamps (3) by means of rivets. Other suitable fastenings may be employed for both the blade (1) and the 100 ejector (2) if desired. It is essential that the perforating blade (1) and ejector (2) shall be fastened to the metal clamps (3) in such a manner and in such positions that they shall operate so closely together that 105 the blade (1) will just clear the ejector (2); and that the correct tension shall be maintained on both to prevent buckling and to insure a proper functioning of each, thus securing an exact perforation of the paper 110

or other similar substance used, and to secure a perfect and instantaneous stripping thereof from the blade (1) and the type (11). It is also necessary that the clamps 5 (3) shall be so made and formed to the grippers (5) that the clamps (3) may be slipped on over the ends of the grippers (5) to an exact position thereon to enable a proper tension to be kept on the clamps (3), 10 the perforating blade (1), and the ejector (2), and to insure a proper contact being made between the back of the perforating blade (1) and the metal base (4) which is locked in the form in the chase (9) with 15 the type (11) and the furniture (10); the chase (9) is secured to the bed (7) of the press in the usual way. The proper location 20 of the clamps (3) on the grippers (5), with the other parts mentioned in positions as stated is essential to insure a correct and exact perforation, cutting or scoring of a line between any two printed lines as close together as one sixth of an inch.

The perforating blade (1) preferably 25 shall be one quarter of an inch greater in length at each end than the ejector (2), but if desired this distance may be increased.

By using a heavy tympan sheet (8) and

a suitable metal base (4) of type metal or other similar substance, the perforation, cutting or scoring of paper or other similar substances used in the printing art up to a thickness of about equal to three ply bristol board is accomplished.

I am aware that prior to my invention 35 other perforating, cutting and scoring devices have been made, but none that I know of that may be operated with platen printing presses simultaneously with the printing operation, without injury to the inking rolls 40 to accomplish the perforation, the cutting or scoring of a line to that degree of closeness to the printed lines, nor as an auxiliary gripper with an ejector, and I therefore 45 claim:

A combination of two metal clamps with a metal ejector bar attached at each end of the lower side of said clamps at the inner ends thereof, together with a metal perforating, cutting or scoring blade attached at each 50 end to the upper side of said clamps also at the inner ends thereof, and all in combination with a suitable metal base, all substantially as described.

C. R. BROWN.
